(57) **CLAIM**

We claim ornamental design for a handgun slide, as shown and described.

DESCRIPTION

FIG. 1 is a perspective view of a handgun slide showing our new design;

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

The broken line in the drawings depicts unclaimed subject matter that forms no part of the claimed design.

1 Claim, 7 Drawing Sheets
